Kenneth S. Vernam, Bronxville, N. Y., assignor to Wallach's, Inc., New York, N. Y., a corporation of New York

Application August 12, 1953, Serial No. 26,434

Term of patent 14 years

(Cl. D3—13)

To all whom it may concern:

Be it known that I, Kenneth S. Vernam, a citizen of the United States, residing in Bronxville, county of Westchester, State of New York, have invented a new, original, and ornamental Design for a Cap, of which the following is a specification, reference being had to the accompanying drawing, forming part thereof, in which:

Fig. 1 is a front view in perspective of a cap embodying my new design;

Fig. 2 is a side elevational view of same; and

Fig. 3 is a top plan view of same.

I claim:

The ornamental design for a cap, substantially as shown.
